UNITED STATES PATENT OFFICE.

HAROLD M. STUELAND, OF CLARKFIELD, MINNESOTA.

COOLING FAN FOR MOTORS.

Application filed August 10, 1921. Serial No. 491,118.

To all whom it may concern:

Be it known that I, HAROLD M. STUELAND, a citizen of the United States, residing at Clarkfield, in the county of Yellow Medicine and State of Minnesota, have invented certain new and useful Improvements in Cooling Fans for Motors, of which the following is a specification.

This invention relates to cooling fans for 10 motors and more particularly to an apparatus adapted to be operated for adjusting or reversing the blades on the fan which are employed for cooling the motor.

Other objects of the invention will appear 15 upon consideration of the following detail description and accompanying drawings, wherein:—

Figure 1 is a plan view,

Figure 2 is a cross section taken on the 20 line 2—2 of Fig. 1,

Figure 3 is a side elevation partly in section,

Figure 4 is a cross section through the sliding block, and

25 Figure 5 is a perspective view of one of the fan blades.

Referring to the drawing by numerals, the shaft 1 is square in cross section and is equipped with a sliding block 2 which consists of a square member having a square central opening 3 through which the shaft 1 extends. At opposite faces, the block is provided with screw threaded recesses 4, a stud 5 extending centrally through circular 35 movable disks 6 on the faces of the said sliding block and are engaged with the fan blades 7 as shown. Each fan blade 7 comprises a metallic blade of suitable length having a cut out portion 8 and provided 40 with transverse slits for the purpose of permitting the material at the center of the blade to be pressed outwardly in opposite directions to form a series of holding elements for the extended end of the stud 5, thus securing the fan blades to the member 5. The fan blades are also attached to the 45 movable disks 6 by the lugs or ears 9 on the ends of the blades which are provided with suitable fastening members for securing the 50 blades in position. By this arrangement it will be noted that the disks 6 may be turned to change the angle of the fan blades on the stud 5.

At one end of the shaft 1 is a square block 55 10 which is fixed to the shaft and has at-

tached thereto the arms 11 which in turn are connected by the projecting members 12 carried by the disks 6 so that when the block is longitudinally moved on the shaft 1, the arms 11 engaging the members 12 will cause the disks to turn, thus turning the fan blades to change the angle of the same. A coil spring 13 is interposed between the member 10 and the block 2 to normally urge the block to a position away from the block 10.

The usual belt pulley 14 is mounted upon the shaft whereby the shaft may be rotated, and one end of the block 2 is provided with a collar or sleeve 15 having diametrically opposite pins 16 which are connected to the 70 fork ends 17 of an operating lever 18 which is pivotally mounted upon a bracket 19 as shown in Fig. 1. This lever is connected by an operating rod 20 which extends to a point within reach of the driver of the vehicle whereby the apparatus may be operated. 75

Minor changes may be made in the details of construction without departing from the spirit of the invention or the scope of the 80 claims hereunto appended.

What is claimed is:—

1. An adjustable fan for motors comprising a rotating shaft, a block secured stationary to one end of said shaft, a fan hub slidably mounted on the shaft, a coil spring urging said fan hub from said block, a plurality of studs fastened into the said hub, fan blades mounted on said studs, movable plates between the fan hub and fan blades, means for securing the blades to the plates, arms connecting the said plates to said block, and means for sliding said fan hub upon the revolving shaft to change the angle of said blades. 95

2. In combination a rotating shaft, a block secured to one end of the shaft, a hub slidably mounted on the shaft, a plurality of fan blades rotatably connected to the said hub, plates on said hub for rotating the said fan blades, a plurality of arms connecting the plates with the block, a coil spring between said block and fan hub, a rotatable collar carried by said hub, pins extending from the collar, a forked member engaging 100 said pins, means for supporting the forked member, and means for actuating same to move said hub upon said shaft to change the angle of the blades. 105

3. A device of the character described 110

comprising a rotating shaft, a hub slidably mounted on the shaft, a plurality of studs threaded into the hub, fan blades mounted on the studs by having slits formed therein and the portions between said slits bent in opposite directions so as to form aligning openings for receiving said studs, plates on said hub having extending arms secured to the fan blades, means for sliding the hub upon the rotating shaft, a coil spring acting

against sliding movement of the hub, a block rigidly secured to the shaft, and arms connecting the said block and the movable plates.

In testimony whereof, I have affixed my ¹⁵ signature in the presence of two witnesses:

HAROLD M. STUELAND.
